PREFABRICATED BUILDING UNIT AND WALL

Meier G. Hilpert, Bethlehem, Pa.

Application February 3, 1937, Serial No. 123,931

8 Claims. (Cl. 72—1)

This invention relates to slabs, capable of varied uses but especially intended for use in forming the walls, floors and roofs and the floors plus ceilings and the roofs plus ceilings, of pre-fabricated building constructions preferably having steel frames and if desired, stucco, or "Gunit," or brick veneer exterior finishes, and has generally in view to provide for these purposes strong, light weight, low cost, weatherproof, heat and sound insulating slabs and a novel method 10 of producing the same; also, to provide a novel method and means of joining said slabs together.

With the foregoing general object in view, the invention consists in a slab having the novel combination and arrangement of features, and in the novel slab production method, as will be hereinafter more fully described, illustrated in the accompanying drawings and defined in the appended claims.

20 In the drawings:

Figure 1 is a plan view of a grid-like reinforcement for the top or outer wall of a slab.

Figure 2 is a plan view of a grid-like reinforcement for the bottom or inner portions of the 25 side and end walls and the ribs of a slab, including chairs for the attachment of additional reinforcements.

Figure 3 is a longitudinal sectional view showing the relative arrangement of the reinforcing elements of Figures 1 and 2 and cell forming core elements within a form preparatory to pouring the body portion of one of the present slabs.

Figures 4 and 5 are fragmentary sectional and 30 plan views, respectively, of a combined clip and chair used in the construction of the present slab.

Figure 6 is a plan view of a completed body portion of a floor or roof slab.

Figure 7 is a longitudinal section through a completed body portion of a floor or roof slab 40 with the cell forms and exterior forms removed and provided with thermal insulation.

Figure 8 is a longitudinal section through a finished floor or roof slab showing the plastic cast ceiling forming closures for the cells thereof.

Figure 9 is a fragmentary sectional view showing a joint between two adjacent floor or roof slabs.

Figure 10 is a view similar to Figure 9 illustrating an alternative slab and joint construction.

Figure 11 is a plan view of a wall slab equipped with a hole for the reception of a lifting device and with anchors for retaining a stucco, "Gunit," or brick veneer exterior finish.

Figure 12 is a transverse section on the line 12—12 of Figure 11.

Figure 13 is a view similar to Figure 12 showing a modification in applying thermal insulation.

Figure 14 is a sectional view through a wall slab.

Figure 15 is an elevation of a wall having slab load and locking elements extending between the slabs forming said wall.

Figure 16 is a horizontal section through the wall joint showing the loading and locking elements in elevation.

Figure 17 is a sectional, perspective view of a portion of a building constructed with slabs and elements in their proper relation to a steel frame all in accordance with the invention.

Referring to the drawings in detail, first with particular reference to the floor or roof, or floor plus ceiling, or roof plus ceiling, slab illustrated in Figures 6 to 10, A designates, generally, the slab body which in accordance with the invention, is of rectangular shape and may be formed from any suitable material such as ordinary concrete or the like, or cinder concrete, "Haydite" or the like having thermal insulating value in itself.

The body A may be of any desired length, breadth and thickness and is of closed top, cellular construction having the cells thereof opening through its bottom. That is to say, the body A comprises a top wall 10, side walls 11 and end walls 12, and has depending from its top wall to the plane of its bottom, one or more strengthening ribs 13 extending longitudinally from end to end thereof, and one or more strengthening ribs 14 extending transversely from side to side thereof, the said ribs cooperating with each other and with the side and end walls to define the cells, designated as 15, which open through the bottom of the body A as stated.

In the top wall 10 is embedded suitable reinforcing means which conveniently may comprise a plurality of rods 16 and 17 extending longitudinally and transversely of said wall, said rods 16 and 17 preferably, but not necessarily, being suitably joined together at the points where they extend across or intersect each other. In addition, other reinforcing rods 18 and 19 are embedded in the bottoms of the ribs 13 and 14, respectively, and extend longitudinally thereof, said rods 18 and 19, as in the case of rods 16 and 17, also preferably, but not necessarily, being suitably joined together at the points where they extend across or intersect each other.

On some or all of the rods 18, at points spaced therealong, are engaged clips 20 having eye portions 21 which extend transversely relative to said rods 18. Conveniently, these clips 20 may be formed from sheet metal as illustrated in Figures 4 and 5 of the drawings.

Extending through the eye portions 21 of the clips 20 from side to side of the slab body A are rods 22 which serve as reinforcements for a relatively thin slab bottom closure 23 of cement or the like having at the bottom thereof additional transversely extending reinforcing rods 22'.

In some cases it may not be necessary or desirable to have finished ceilings at the under sides 15 of the floor or roof slabs A. On that event, in forming the slabs, the rods 18 need not be equipped with the clips 20 for holding the rods 22 and said rods 22 and the bottom closure 23 need not be provided. In other words, the cells 15 20 may remain open at their bottoms. On the other hand, in cases where it is necessary or desirable to have finished ceilings at the under sides of the slabs A, the bottom closures 23 therefore and the reinforcing rods 22 held by the clips 20 or 25 their equivalent are provided, the said bottom closures forming the finished ceilings as is apparent.

Preferably the cells 15 are lined with metallated paper or other suitable material 24 whereby the 30 heat losses of the slab are greatly reduced and moisture and air are prevented from finding their way through the slab. Alternatively, the cells 15 may be filled, or partly filled, with other suitable heat and sound insulating material such, 35 for example, as bulk insulation, designated as 25, which may be retained in said cells in any suitable manner, as, for example, by being stuck to the interior cell walls before applying the closure 23, or by means of bowed rods or wires 26 engaged 40 at their ends against the cell side and, or, end walls, as illustrated in connection with the wall slab shown in Figure 12, or alternatively, the bulk insulation may be carried on a sheet of paper resting on the rods 22 and provided with 45 upturned edges, or it may be placed on top of and around the sides of the core elements employed in forming the slab, prior to the pouring of the material to comprise the slab over said core elements.

The slabs A are adapted to be suitably supported in side to side and end to end relationship 50 with their ends resting upon the flanges of beams or girders, and are adapted to have the spaces between them filled by concrete or other suitable material which may present either the same surface color as the slabs or any contrasting color 55 to form an attractive floor design. In any event, to adapt the slabs, when disposed in side to side and end to end relationship, to have spaces 60 formed therebetween for the reception of slab binding fillers of concrete or the like, the outer faces of the side and end walls of the slabs, according to one practical form of the invention, are downwardly and outwardly inclined as indicated at 27. This results in the forming, between any two adjacent slabs, of a V-shaped channel for the placing of I-beam tie rods and 65 for the reception of a binding material designated as 28, which may, if desired, be covered by a reinforced layer 29 of the same material as the slab body. Moreover, this beveling or inclining of the side and the end walls of the slab body provides for the forming of a binding material receiving channel between the side or end of any 70 terminal slab, as the case may be, and an I-beam 75

or the like on the flange of which the side or end of the slab rests, the I-beam or the like being thus fireproofed by said binding material.

Obviously, instead of beveling the sides and ends of the slab body to provide for the forming of binding material receiving channels between the slabs, the same result may be obtained by forming the bottom portion of the slab body at its sides and ends with an outwardly directed flange 30, in which event the outer faces of the slab body above said flange may be either perpendicular to the plane of the slab body, or inclined, as may be desired. In either case, when the flanges of any two slabs are brought into edge to edge abutting relationship, as illustrated in Figure 10, a binding material receiving channel is formed between the slabs as is apparent. Also, it is apparent that in the case of any terminal slab resting upon the flanges of I-beams, or the like, there is formed a binding material receiving channel between the adjacent wall or girder and the side of the slab body.

In Figures 11 to 16 of the drawings are illustrated wall slabs, designated as B, which are of generally the same construction as the floor or roof, or floor plus ceiling, or roof plus ceiling slabs illustrated in Figures 6 to 10. That is to say, the bodies of said wall slabs are of rectangular shape and may be formed from any of the materials from which the slabs A are formed. Moreover, they may be of any desired length, breadth and thickness and are of closed outer side, cellular construction having the cells 15' thereof formed by longitudinally and transversely extending ribs, 13' and 14' respectively, integral with and extending inwardly from their closed outer sides 10'. At their inner sides they may be either left open or unfinished or they may be closed by thin walls 23' as in the case of the slabs A. Moreover, the cells 15' may be lined with metallated paper or may be filled, or partly filled, with bulk insulation which may be retained in said cells in any suitable or desired manner. Instead of the edges of the slabs B being beveled or stepped as in the case of the slabs A, the edges 4 of said slabs B preferably are flat and are disposed perpendicularly to the planes of the slabs.

As it is intended that the wall slabs B are to be made of considerable size they may be quite heavy and, in the absence of special means to facilitate their handling, they may be difficult to handle. Accordingly, and as illustrated in Figures 11 and 12 of the drawings, there preferably is formed through each slab B, transversely thereof, a hole 31 through which a rod, pipe or the like may be passed for use in lifting or otherwise handling the slab. This hole may be formed at any desired point. Preferably, however, it is formed approximately midway between the ends of the slab, through one of the ribs 13' or 14' or at a point where a pair of these ribs intersect. Moreover, the concrete or other material comprising the slab body preferably is reinforced adjacent to said hole as illustrated, for example, in Figure 12, by means of a rod or wire 32 bent upon itself and embedded in one of the ribs 13 or 14 and having eye or ring-like formations 33 embedded in the material of the slab body in surrounding relationship to the hole.

While a slab A or B embodying a construction 70 in accordance with the invention may be formed in any desired manner, a simple, cheap and easy method of forming the same is illustrated in Figures 1 to 3 of the drawings: A suitable form F is provided and this is provided either with a

flat bottom or is disposed upon a suitable flat surface *s*. In addition, there is provided, as illustrated in Figure 1, a section of the crossed rods or wires 16, 17 substantially corresponding in length and width to the top wall 10 of the slab body to be formed, and, as illustrated in Figure 2, a section of the crossed rods or wires 18, 19 spaced correspondingly to the spacing of the ribs 13 and 14 to be formed, the wires or rods of said sections being wire tied together so that they may readily be adjusted relatively to each other for use in forming slabs of different sizes. Moreover, there are provided a number of closed-top, closed-side, pan-like elements 35 to serve as cores for forming the cells 15. At points suitably spaced along the wires 18 or 19, depending upon whether it is desired that the bottom closure reinforcing rods 22 shall extend transversely, or longitudinally of the completed slab, are placed the clips 20 in aligned rows transversely or longitudinally of the crossed rod or wire section as the case may be, and said section is placed within the form *F* with the eye portions 21 of the clips 20 resting on the surface *s*, and serving as chairs supporting the rods 18 and 19 slightly above said surface. Within the rectangular space between each two adjacent rods 18, 18 and 19, 19 is placed one of the pan-like core elements 35, the same resting on the surface *s* and having downwardly and outwardly sloping side and end walls of which the side walls engage the ends of the clips 20, whereby said core elements are held properly positioned relative to the rods 18. As is understood, the pan-like elements 35 are arranged in rows longitudinally and transversely with the elements spaced apart corresponding to the width of the ribs 13 and 14 to be formed. For either of the slabs A or B there may be disposed in covering relationship to each core element a sheet of the metallized paper or the like 24. Supported in any suitable manner at suitable distances above the tops of the core elements 35 is the grid-like section of crossed rods or wires 16, 17. In addition, if the slab is to be provided with the hole 31 a suitable core, such as an ordinary paper mailing tube, is placed in upright position at the point where the hole is to be located and the reinforcing wire or rod 32 is supported in proper position by means of said core. The concrete or other material from which the slab is to be formed then is mixed, or, already mixed and in plastic condition, is poured into the form *F* until it fills the spaces between the core elements 35, thereby forming the ribs 13 and 14, or 13' and 14', as the case may be, and until it rises suitably above the tops of the core elements to form the top wall 10 or 10' of the slab body, A or B as the case may be. Thereby, the reinforcing rods or wires 16, 17 become embedded in the top wall 10, and the rods or wires 18, 19 become centrally embedded in the bottoms of the ribs 13, 14 with the eyes 21 of the clips 20 presenting openings at the bottom of and through said ribs to receive the wires or rods 22. Thereafter, the wires 34, if same are used, are forced in the plastic top of the slab body.

After hardening of the concrete or other material from which the slab body is formed, the form *F* is removed, the slab body is lifted from the surface *s*, and the core elements are removed, leaving within the cells 15 for wall slabs the metallized paper or equivalent linings 24. If an alternate thermal insulation is to be used and the cells are to be filled or partially filled with insulating material 25 as for roof or over basement slabs, this material then is placed within said

cells and is suitably secured therein as by placing on paper and resting on rods 22 or by means of the rods or wires 26. The bottom closure reinforcing rods 22 then are inserted through the eyes 21 of the clips 20 and the bottom closure 23 is applied in any suitable manner, becoming united with the slab body through the instrumentality of the rods 22 and the clips 21 and serving effectively to close the bottom of the slab. In this connection one suitable manner of applying the bottom closure 23 is to provide a form corresponding in length and width to the bottom of the slab body; to pour into this form a quantity of the material in plastic form from which the bottom closure is to be formed until the material assumes the form of a sheet of the desired depth or thickness; then to lower the slab body into said form until the bottom of the slab body embeds in the plastic material, and finally to permit the plastic material to harden. This obviously results in the rods or wires 22 becoming embedded in and reinforcing the bottom closure and, at the same time results in the bottom closure becoming securely bonded to the slab body in effective closing relationship to the bottom thereof. As a result the finished slab is of hollow, cellular form, light in weight, strong, weather-proof and may have effective heat and sound insulating qualities if the cells 15 are provided with suitable materials 24 or 25. To additionally reinforce the slab bottom or inner side closure 23 or 23' the cross rods 22' are laid in the bottom of the form to form supports for the slab body, said cross rods 22' thereby becoming embedded in the closure 23 or 23', as the case may be, when the latter hardens.

In the assembling of a prefabricated building it is important that all of the prefabricated wall units be capable of expeditious assembly to promptly provide all exterior and interior surfaces for finishing as a following operation, and that all joints shall be well bonded as against contractive and expansive forces and other forces such as the weight of the units or wind pressure against the wall slabs, or even earthquake forces. Therefore, the wall slabs are provided with flat sides perpendicular to their planes and wire mesh or rods or the like 36 having T-shaped or equivalent ends, is or are employed between adjacent slabs as illustrated in Figures 15, 16 and 17. The rods 36 extend transversely between the slabs at suitably spaced apart intervals and their T-shaped or equivalent ends overlie the inner and the outer faces of the slabs. Thereby, the slabs are supported in slightly spaced apart relationship and are interlocked against lateral movement relative to each other, especially when the T-shaped or equivalent ends of the rods are embedded in stucco and plaster. Moreover, when stucco or the like is applied to the outer sides of the wall slabs and plaster is applied to the inner sides of said slabs, it is pushed into the spaces between the slabs and provides additional bearing area between the slabs and insulating air spaces within the joints. The rods 36, moreover, assure uniform, thin joints between the slabs and permit of assembling the wall slabs very expeditiously without the use of mortar. They also eliminate joint contraction such as would occur with the drying out of mortar if mortar were used. In addition, they serve to bond the exterior finish such as stucco or the like to the interior plaster and thereby assist in eliminating joint cracks in the surface finishes.

It is to be noted that a prefabricated building

constructed with wall, floor and roof slabs as herein described provides interior thin concrete or the like surfaces with most excellent suction for durable interior plastering whether one or more coats, and provides thicker surfaces which may be form-roughened as necessary for durable exterior coatings as stucco or "Gunite" or the like.

As an alternative exterior finish, facing brick or stone or tile may be specified and the bonding thereof to the wall slabs then becomes necessary. For such construction there is embedded at spaced intervals in the exterior face of the wall slabs staple-like anchors preferably of several 10 pieces of galvanized wire twisted together for greater bonding value for both the exposed portion and the embedded portions. As the exterior finish is applied, that is, as the brick veneer wall is laid up, the usual brick wall galvanized 15 wall anchors are made to engage the slab staples and are mortared into the brick wall joints and thus the exterior finish is thoroughly tied to the locked wall slabs and shored against same by the excess veneer mortar bridging, at places, the 20 usual insulating air space between the wall slabs and the veneer wall. The wall slab staples also act as accurate spacers for the width of the air space between the slab wall and the veneer wall, since the staples are placed in the prefabricated 25 wall slabs by shop methods so as to extend exact distances beyond the exterior surfaces of slabs.

For veneer walls it will be provided that the veneer wall be founded slightly below the bottom slab joint and said slab joints thoroughly mortared exteriorly so that moisture invading the 30 air space between the veneer wall and the slab wall will escape through the lower and exterior veneer wall joint, thus avoiding a serious defect of the ordinary veneer wall of brick, stone or tile.

Without further description it is thought that the features and advantages of the invention will be readily apparent to those skilled in the art, and it will of course, be understood, that changes in the form, proportion and minor details of 40 construction may be resorted to, without departing from the spirit of the invention or scope of the appended claims.

I claim:

1. A building slab comprising a body portion 45 having a top or outer wall, side and end walls, and ribs extending inwardly from the top or outer wall and cooperating with the side and end walls to form cells within said body portion, metallized paper linings for said cells, and a bottom 50 or inner side closure for said slab body.

2. A building slab comprising a body portion of closed top hollow form, clips embedded in said

body portion and having eye formations extending beyond the bottom of said slab body, rods extending through said eye formations, and a bottom closure for said slab body in which said rods are embedded.

3. In a wall construction, a plurality of slabs disposed in edge to edge wall forming relationship, and slab spacing means extending between adjacent slabs transversely of the wall and having locking head formations disposed outwardly 10 of the inner and the outer faces of the wall, and cooperating with said faces to hold the slabs against inward or outward movement relative to each other.

4. A building slab having a top or outer wall, 15 side and end walls, and ribs extending from the top or outer wall and cooperating with said side and end walls to form cells within the slab, reinforcement means within the ribs near the bottom or inner ends thereof, and eyed clips, carried by said reinforcement means and extending beyond the bottom or inner faces of said ribs 20 for holding reinforcement means for a bottom or inner side closure for said slab.

5. A wall comprising superimposed pre-formed 25 slabs, slab spacing elements extending transversely of said wall between adjacent slabs holding the latter spaced apart, and formations at the ends of said spacing elements overlying the inner and the outer faces of the slabs and providing retaining and reinforcing means for plaster at the inner side of the wall and a finishing veneer or stucco at the outer side of the wall.

6. A wall as set forth in claim 5 having a finishing veneer or stucco at its outer side and plaster at its inner side, the veneer or stucco and the plaster extending into the spaces between the 30 slabs.

7. A building slab having a hole formed transversely therethrough and opening at opposite 40 sides thereof for the reception of a lifting element, and slab reinforcing means embedded in said slab in surrounding relationship to said hole.

8. A building slab comprising a body portion having a top or outer wall, side and end walls, and ribs extending inwardly from the top or outer wall and cooperating with the side and end wall, to form cells within said body portion, heat and sound insulating material within said cells, yielding means sprung into the cells from the open side thereof to hold the insulation material against said top or outer wall and the side walls of said cells, said yielding means engaging the opposite walls of the cells thereby to be held in place, and a bottom or inner side closure for 50 said body portion and closing said cells.

MEIER GEO. HILPERT.
